BINDING POST UNIT

Howard N. Saxton, La Mesa, Calif., assignor to General Dynamics Corporation, Rochester, N.Y., a corporation of Delaware

Filed Mar. 28, 1957, Ser. No. 649,090

1 Claim. (Cl. 339—253)

This invention relates to a binding post unit adapted for use with and upon electrical apparatus and instruments for securing wire leads and the like to circuit terminals.

In modern day testing and manufacturing of electrical equipment, it is exceedingly imperative to have trouble-free, quick acting and diminutive binding posts in the various applications for these units. Most of the present day binding post units are of a rather complex manufacture, necessitating high initial costs and further, due to their inherent geometry, have considerable waste space attendant their construction. These factors all aid in making present day units rather expensive in initial cost and replacement cost and at times due to their inherent geometry, have considerable waste space attendant their construction. These factors all aid in making present day units rather expensive in initial cost and replacement cost and at times due to their inherent complexity cause malfunctions which often necessitate replacement of the unit. This, of course, requires additional time, further outlay of money for additional units, and, in general economic loss attendant thereto.

The present invention seeks to overcome many of these difficulties by providing a greatly improved binding post unit, which, because of its simplicity, establishes reliability. Further, the inventive binding post unit is one which utilizes the maximum space allocations in the most beneficial manner to achieve the greatest utility in attaining its prime purpose, namely that of holding or binding leads or the like securely.

The instant invention includes a plunger member which has a cylindrical rod element. On at least one end of the rod element is mounted a cylindrical disk element. The outer curved surfaces of these two elements are positioned in substantially longitudinal alignment so that a portion of the longitudinal outer surface of each of the elements lies in a common plane. The result is to have the disk element eccentrically mounted on the rod element with the outer surfaces thereof having a portion in planar longitudinal alignment.

A cylindrical housing is provided to journal therein the disk element, and to permit protrusion through one end of the housing of the rod element in journaling relation with the housing. Intermediate the opposite end of the housing and the disk element is positioned a resilient means capable of holding the disk element against the one end of the housing through which the rod is journaled. The housing has, additionally, a generally transversely positioned receiving slot formed therethrough, which, together with the disk element may cooperate to form a receiving opening for a wire lead, or the like, when the disk element is urged against the resilient member. Release of the disk element will cause, under the influence of the resilient member, the lead to be firmly bound to the housing by the disk element.

In addition to the aforementioned objects and advantages, it is an object of this invention to provide a simple and trouble-free binding post unit.

It is another object of this invention to provide a bind-

2

ing post unit of minimal size dimensions through utilization of eccentrically mounted disk element, which, together with a slot in the housing carrying the disk element holds the wire lead or the like to the unit.

5 It is another object of this invention to provide a binding post unit which is highly adaptable for utilization in present day miniaturization practices.

Objects and advantages other than those set forth above will be apparent when read in connection with the 10 accompanying drawings and specification, in which:

Figure 1 is a view in perspective of a binding post unit embodying the invention;

Figure 2 is a view in perspective of the plunger member of Figure 1;

15 Figure 3 is a reduced exploded view of the invention as shown in Figure 1.

Shown in Figure 1 is a generally cylindrical housing

10 which has journaled therein a plunger member 11 shown in detail in Figure 2. Plunger member 11 and 20 housing 10 have interposed therebetween a resilient means 12. It should be realized that the resilient means 12 shown in the instant embodiment is exemplary and while any known means such as rubber, plastic, metallic, liquid, gaseous or the like, resilient means may be 25 utilized, the embodiment shows a metallic spring as an example.

The housing 10 may, if desired, be part of a substantially unitary body member 14 which includes housing

30 10 and a shank portion 15. Shank portion 15 may include adjacent the housing member, a knurled section 16, and adjacent its terminus, a reduced diameter section 17. Knurled section 16 may be utilized to fasten the unit to another structure, and, the reduced diameter section 17 may be used to permit the attachment of leads, 35 clips or the like for electrical connection of the same with the unit.

The housing 10 may preferably have formed therethrough in a generally transverse position a receiving slot 20. Into this receiving slot 20 will be placed the

40 40 desired leads to be bound to the unit. The housing 10, which may be made by evacuating a portion of its interior may be closed at the end through which it is evacuated or drilled by a cap portion 21.

Plunger member 11 includes preferably a cylindrical 45 rod element 22, and on at least one end thereof a cylindrical disk element 23. While in the instant embodiment the rod element 22 and disk element 23 have been shown as cylindrical, this showing is exemplary only and clearly does not exclude from the invention any other desired 50 shapes such as rectangular, triangular and the like. There may be placed on the opposite extremity of rod element 22 another disk element 24 to aid a user in manual depression of plunger member 11 against the resilient means 12. To effectuate the objects of this in-

55 vention, plunger member 11 has its disk elements 23, 24 eccentrically mounted on the rod element. The rod element 22 which has an outer curved surface 26, and the disk elements 23, 24 which have outer curved surfaces 27, 28, are so positioned upon the rod element

60 60 22 as to align the outer surfaces 27, 28 with the surface 26 in planar longitudinal alignment. This, in effect, minimizes the area within the housing member which must be utilized by the plunger member for its operation and permits the maximum use of the remaining dis-

65 placement within the housing member to be utilized by the receiving slot 20 for introduction thereto of the desired wire lead or the like.

In operation, the plunger member 11 may, by urging

70 70 on disk element 24 be depressed against resilient means 12 thereby moving disk element 23 below the slot 20. This permits introduction of a wire lead into slot 20. Release of plunger member 11 will effect binding of the

wire lead to the slot 20 by disk element 23, thereby effecting both a mechanical and an electrical binding of the lead to the binding post unit.

A particular embodiment of the invention illustrated and described herein is illustrated only, and the invention includes such other modifications and equivalents as may readily appear to those skilled in the art within the scope of the appended claim.

I. claim:

The combination comprising: a tubular housing 10 having a transversely positioned wire receiving slot through the wall thereof; a cap positioned on the end of said housing, said cap having an eccentrically positioned hole therethrough; means for forcing a wire to the end of said slot, said means comprising a unitary disk-and-plunger assembly positioned in said housing, said disk having a periphery slightly smaller than the inner periphery of said housing and being coaxial therewith—whereby it may slide freely therein; and resilient means positioned in said housing for urging said disk toward 15 said cap and forcing the wire to the end of said slot; and means for preventing rotation of said disk-and-plunger assembly, said means comprising said plunger.

projecting through said eccentric hole in said cap and being eccentrically positioned with respect to said disk-and-housing and being positioned so that one surface thereof is in slidable contact with the inner surface of said housing—whereby movement of said disk-and-plunger assembly against the force of said resilient means away from said slot permits the wire to be inserted into said slot, and movement of said disk-and-plunger assembly due to said resilient means holds the wire at the end of said slot.
